UNITED STATES PATENT OFFICE.

JOHN WIGHTMAN, OF NOTTINGHAM, ENGLAND.

DESIGN FOR RUFFLING AND RUCHING.

SPECIFICATION forming part of Design No. 21,563, dated May 24, 1892.

Application filed April 20, 1892. Serial No. 429,957. Term of patent 3½ years.

To all whom it may concern:

Be it known that I, JOHN WIGHTMAN, a subject of the Queen of Great Britain, residing at Nottingham, England, have invented and 5 produced a new and original Design for Rufflings and Ruchings, of which the following is a specification, reference being had to the accompanying drawing, forming a part thereof, which represents a perspective view of a piece 10 of ruching embodying the features of my design.

The design consists of fringe-like practically-circular figures A, having a feathery appearance and arranged in a row along the

edge of a band-like figure B, apparently overhanging a face of the band, and a series of puff figures D, apparently forming a portion of the band and located below the line of fringe-like figures, the fringe-like figures appearing to curl over and form a festoon above 15 the puff figures.

I claim—

The design for ruffling and ruching, as herein shown and described.

JNO. WIGHTMAN.
